WALL OPENING ENCLOSURE

James E. Patterson, Washington, D. C., assignor
to George F. Garwood, Salt Lake City, Utah

Application February 8, 1936, Serial No. 63,006

22 Claims. (Cl. 189—64)

The present invention relates to a closure for openings, and more particularly to openings in buildings and the like wherein it is desirable at times to provide a comparatively wide opening which may be quickly, conveniently, and securely closed when desired.

In building structures, particularly store fronts and similar constructions, it is desirable to open the front completely without any objectionable projections extending across the opening, while at the same time providing means whereby to close or partly close this opening in cold or inclement weather, or when shutting up the shop or store at the end of the day.

It has been proposed in certain constructions to provide a plurality of hinged closure members either in the form of multiple doors or windows hinged at their edges to each other so as to be extensible across the opening, or to utilize individual closure members which hinge to the upper part of the opening or supporting structure. Vertically movable sliding sash members have also been proposed in which the guiding supports therefor are carried by the building structure above the opening.

None of the above constructions has been found to be entirely satisfactory due to the fact that these constructions are very unsightly and difficult to operate, but possibly the most serious drawback is that the structures mentioned are inherently weak or frail and may be easily broken or damaged by storms, etc.

No satisfactory means has ever, so far as I am aware, been devised whereby a comparatively large building structure opening, such as a long, unobstructed shop or store counter, may be quickly and easily converted into a closed store front having mullion members extending across the opening and sash members therebetween, the structure, when so converted, having all of the strength and rigidity of constructions wherein permanent mullion members are utilized in conjunction with sliding sash members.

An object of my invention is, therefore, to provide a construction wherein a building structure having a comparatively wide, unobstructed opening may be quickly and easily converted into a fully or partly closed opening, as desired.

Another object is the provision of a closure for openings in building structures having a plurality of sash members which are movable across the opening to close the same, together with intermediate movable guide means or mullion members also movable across the opening to provide a rigid guiding support for the sash members

when so moved, the sash members and guide means when in one position leaving a free and unobstructed opening.

A further object of the invention is the provision of a counter having an unobstructed opening above the same, vertically guided movable mullion members which may be projected across the opening into engagement with the counter, and sliding sash members guidingly supported by the mullion members and movable across the opening to close or partly close the same.

A still further object is the provision of stationary or fixed mullion members which project partly across a counter opening above the base support, there being pivoted sash members between these mullions, the fixed mullion members constituting guiding supports for a plurality of telescopically-arranged sliding mullion members adapted to be projected across the opening into locking engagement with the counter or base support, so that a plurality of extremely rigid vertical mullion members are provided, there being sliding sash members which are guided by the telescopic mullion members, both the sash members and their guiding mullion members being shiftable upwardly out of the opening to provide a free and unobstructed, comparatively wide counter space when so moved.

A further object is to provide in an unobstructed building structure opening a mullion member which is movable across the opening, and a sash member also movable across the opening, the sash member being guidingly supported by the mullion member, and separate counter-balancing means for the sash and mullion members to permit easy and convenient shifting thereof.

Another object is to provide locking means for the movable mullion member and for the sash so that, when the same are moved to closed position, they may be securely locked in this position.

Other and further objects and advantages of the invention will be hereinafter described, and the novel features thereof defined in the appended claims.

In the accompanying drawings,

Figure 1 is a perspective view of a corner building structure having my invention incorporated therein and showing certain of the window closure members in fully open position, and other of the closure members in partly closed or fully closed positions.

Figure 2 is an enlarged, fragmentary, front elevation showing one of the window closure members and its cooperating sliding mullion sup-

5

ports in fully closed position, and also disclosing portions of the adjacent sliding sash or closure members.

Figure 3 is a vertical sectional view taken approximately on the line 3—3 of Figure 2, the sliding and pivoted sash members being omitted.

Figure 4 is an enlarged, vertical, sectional view taken on the line 3—3 of Figure 2, parts being broken away and the upper or hinged sash member being shown in dotted lines in open position.

Figure 5 is a horizontal sectional view taken approximately on the plane indicated by the line 5—5 of Figure 4, and looking in the direction of the arrows.

Figure 6 is a similar sectional view taken on line 6—6 of Figure 4 but with the sliding sash members in raised position.

Figure 7 is a fragmentary, vertical, sectional view on the line 7—7 of Figure 5.

Figure 8 is a fragmentary, vertical, sectional view taken on the line 8—8 of Figure 6.

Figure 9 is a fragmentary, vertical, sectional view taken on the line 9—9 of Figure 4, certain of the parts being shown in elevation.

Figures 10, 11 and 12 are fragmentary, sectional views taken on the lines 10—10, 11—11, and 12—12 respectively of Figure 9.

Figure 13 is an enlarged, fragmentary, vertical sectional view taken approximately on the plane indicated by line 13—13 of Figure 2, certain parts being shown in elevation and disclosing more particularly the locking instrumentalities for the telescopic mullion members.

Figure 14 is a vertical, sectional view taken on the line 14—14 of Figure 13, certain parts being shown in elevation.

Figure 15 is a fragmentary, horizontal, sectional view taken on the line 15—15 of Figure 13.

Figure 16 is a fragmentary, horizontal, sectional view taken on the line 16—16 of Figure 13.

Figure 17 is a vertical, sectional view taken on the plane indicated by line 17—17 of Figure 14, and showing the locking means for the telescopic mullion members in released position.

Figure 17A is a sectional view similar to Figure 17, but showing the socket closure member in the counter for the mullion locking bolt in its raised or socket-closing position.

Figure 18 is a horizontal, sectional view taken on the line 18—18 of Figure 13.

Figure 19 is a fragmentary, vertical, sectional view taken through one of the sliding sash muntins.

Figure 20 is a fragmentary, detailed view of the end portion of one of the sash slot closure members.

Figure 21 is a similar view but taken at right angles to Figure 20.

Figure 22 is a fragmentary, horizontal, sectional view taken about on the line 22—22 of Figure 2 and looking downwardly, and showing a slightly modified form of sliding sash and mullion construction, the sliding sash members being raised and shown in section.

Figure 23 is a fragmentary, sectional view disclosing a slightly modified embodiment of my invention, and taken on the horizontal plane below the sectional plane of Figure 22 and looking downwardly.

Figure 24 is a fragmentary, horizontal sectional view taken approximately on the plane indicated by line 24—24 of Figure 23 looking downwardly in the direction of the arrows.

Figure 25 is a fragmentary, sectional view sim-

ilar to Figure 23, but taken on a still lower sectional plane.

Figure 26 is a vertical, sectional view taken through a window opening of the modified embodiment, certain of the parts being broken away.

Figure 27 is a detailed view of the swinging sash retaining latch and sliding sash locking means, and

Figure 28 is a detailed, vertical, sectional view of a slightly modified form of sliding sash lower sealing means.

Like reference characters designate corresponding parts in the several figures of the drawings.

Referring to the drawings, 1 designates the exterior corner walls of a building structure having an opening indicated generally at A, which is adapted to be closed by the sash closure members 6. Referring more particularly to Figure 1 of the drawings, the reference character 2 indicates one of the sash closure members and its adjacent telescopically-arranged guiding mullions 5 in fully extended position closing that portion of the opening A, while the reference characters 2a, 2b and 2c indicate three adjacent closure members and their guiding mullions in fully raised position, thereby leaving that portion of the opening free and unobstructed. The reference numeral 2d indicates one of the closure members in partly raised position, leaving an unobstructed opening although more restricted in height above the counter or shelf 3, as seen in Figure 1 of the drawings.

While I have illustrated a counter somewhat elevated from the floor or ground level, it is to be understood that this counter may be dispensed with and a base member disposed level with the floor or ground substituted therefor where it is desirable to provide an entrance or passageway instead of the store or shop window opening, as shown.

Referring now more particularly to Figures 1 to 7 of the drawings, I preferably employ a plurality of fixed mullion members 4 which are suitably secured by bolts 7a in the supporting structure or framework 7 above the window opening A. Plate washers 7b and suitable lock washers 7c may be provided for securing the bolt members 7a against displacement and for properly alining the fixed mullion members with respect to the supporting framework.

These fixed mullion members are preferably of U-shape channel construction, as seen in Figure 6, and extend downwardly a short distance across the opening, as seen in Figures 1 and 4, and are provided with a channel-shaped meeting rail or tie member 4a extending therebetween, which is preferably of U-shape construction and provided with weep holes 4b. A felt sealing strip 4c is disposed in the channel for engagement with a sealing member fixed to the top of the vertically slidible sash 6. Pivotally mounted in the upper portion of the opening formed between the fixed mullions are pivoted or hinged closures or transom members 6b, later to be described in detail. The fixed mullion members extend upwardly into the super-structure above the opening a considerable distance, as seen in Figures 2 and 3 of the drawings, and have secured to the end thereof a supporting plate 4f on which is fixed the sliding sash spring balance units B' and the spring balance unit B for counterbalancing the weight of the telescopic mullion member 5. These balancing units are of standard construction and

are not described in detail other than to indicate that they are provided with sash tapes $11d$ suitably connected to the sliding sash, and the flexible connecting member or tape $11c$ connected to a cross pin $11b$ carried by the upper end of the movable mullion member 5 .

The fixed mullion members 4 have secured to opposite exterior sides thereof guide strips $4e$ having their lower ends tapered, as seen more clearly in Figure 4 of the drawings. Similar guide strips $4d$ are secured adjacent the inner free edges of the fixed mullion members for retaining the telescopic or movable mullion members 5 in proper sliding relation therein.

Secured to the lower end of the fixed mullion members 4 are guide shoes $4g$ having substantially the cross sectional configuration of the telescopic mullion members 5 , and each of the movable mullion members 5 comprises the substantially channel shape section $5a$ which is welded or otherwise rigidly secured between the flanges of the member 5 , as best seen in Figure 6 of the drawings. A parting strip $5b$ is fastened to the rear exterior face of the channel portion $5a$ and constitutes the lateral movement limiting means for the sliding sash members 6 , the flanges thereof having a sliding engagement with the sides of this strip. An inverted, U-shaped channel section or weather strip $5c$ is disposed adjacent the rear face of the channel $5a$ and held in normally spaced relation therefrom by spacing collars $5i$. A bar member $5d$ is carried in the upper portion of the movable mullion member and has suspended therefrom a longitudinally-disposed clamping bar $5e$ threaded to receive the screws $5f$ having their heads suitably fixed in the channel section $5c$.

Coiled springs $5h$ are carried by the screws $5f$ and are interposed between the clamping bar $5e$ and the interior face of the channel-shaped section $5a$ forming the rear wall of the movable mullion member. The tension of these springs $5h$ tends to urge the clamping bar $5e$ to the right, as seen in Figure 7, and in this manner the channel section or weather strip $5c$ is urged inwardly against the projecting edges or flange members on the sliding sash members 6 .

The upper end of each of the sliding mullion members has fixed thereon a guide plate or shoe $5g$ having an exterior configuration which is similar to the interior shape of the fixed mullion members 4 . The guide plate $4g$ on the lower end of the fixed mullion member 4 , and the guide plate $5g$ on the upper end of the movable mullion member 5 constitute the guiding means for the movable mullion member to retain it in proper vertical alignment throughout its range of movement.

The upper swinging sash or transom $6b$ is carried by a rigid, square shaft 8 , as better seen in Figures 4, 9, 10 and 11 of the drawings, this shaft being fixed in squared openings in the side flanges of the fixed mullion member 4 . A bushing member $8a$ is carried by this shaft adjacent the U-shaped stop rails $6'$ for limiting the inward movement of the transom sash members $6b$. These bushing members have a cylindrical sleeve bearing to receive the sash bearing members $6c$ fastened to the vertical edges of the transom 6 . Each of these sash bearing members is formed with a shouldered hub $8b$ having a slot $8d$ formed in the hub to receive the end of a torsion spring $8c$ for moving the transom sash to open position, as shown in dotted lines in Figure 4 of the drawings, in order to permit the sliding

sash member to move upwardly through the opening in the upper portion of the super-structure when it is desired to fully raise the sash.

The other end of the torsion spring $8c$ is fixed in a corresponding notch $8d$ formed in a hub member 9 having an enlarged, cylindrical opening $9a$ which receives the flanged hub $9b$ mounted on the shaft 8 and provided with a squared, central opening to fit the shaft. Both the hub member $9b$ and the enlarged portion having the cylindrical opening are provided with radial holes or apertures $9c$ in order that the hub member 9 may be rotated to properly tension the spring $8c$, whereupon a pin member may be inserted through the apertures $9c$ in order to interlock the hub member 9 to the shaft.

For the purpose of preventing lateral displacement between the sash member, the shaft 8 and the fixed mullion member, I mount on the shaft a collar $9e$ having an annular groove $9g$ adapted to receive the recessed extremity of the angle plate $9f$ secured to the upper flange of the pivoted sash.

Mounted between the fixed mullion members 4 and above the pivoted sash member $6b$, as clearly seen in Figures 4, 10, 11 and 12 of the drawings, is an inverted, U-shaped channel 10 . A closure bead or strip $10a$ is secured to the upper frame of the super-structure against the outer face of this U-shaped channel, and a suitable corking medium $10b$ is inserted between the U-channel and the frame of the super-structure. In order to close the space between the upper portion of the pivoted sash and the U-channel 10 , I secure to the U-channel a resilient plate $10d$ which may be removed, when desired, to permit ready access to the spring member 8 for the transom sash for adjustment thereof.

Referring more particularly to Figures 13 to 18 of the drawings, I provide suitable locking means for rigidly retaining the extensible mullion members in their extended positions, together with readily releasable means for releasing the engagement just described to permit the mullion members to be raised or retracted. This mechanism will now be described. Secured in the lower extremity of each of the mullion members 5 is a foot piece or closure 12 held in position by screws $12a$. A second foot piece $12b$ is secured to the rear face of the mullion member 5 directly below the end of the weather strip channel $5c$. Suitable finger-engaging hooks or lifts $12c$ are provided for raising the mullion members. Vertically journaled in the bushing $12e$, screw-threaded in place in the lower face of the foot piece 12 , is a semi-rotatable locking shaft or bolt $12d$ having its upper end journaled in the cover plate $12f$, which also constitutes retaining means for the forked rack locking bolt release member $12g$. The teeth $12h$ of the rack are disposed in meshing relation with an arcuate rack $12'$ formed on the upper extremity of the rotatable shaft $12d$. The shaft $12d$ is provided with an enlarged, intermediate portion $12k$ which is rotatably journaled in the bushing $12e$. A spring member $12''$ surrounds the portion of the bolt between the enlarged part $12k$ and the arcuate rack $12'$, and has one end thereof secured in an opening provided in the foot piece 12 , the other end of the spring being inserted in a vertical socket formed in the enlarged part $12k$, just mentioned. The lower extremity of the shaft 12 terminates in an enlarged head providing a latch-engaging shoulder $12m$ and an oppositely disposed latch release cam $12n$, the release cam being disposed

slightly above the shoulder. From the drawings it will be observed that this semi-rotatable shaft constitutes a locking bolt which projects downward somewhat below the lower extremity of the sliding mullion member 5. The base member or counter 3 is provided with a flanged tube or socket member 13 arranged to receive the locking bolt or shaft 12d, as clearly seen in Figures 13 and 14 of the drawings. I preferably provide an annular gasket member 12l surrounding the bolt 12d and arranged for weather sealing engagement with the counter or base member 3.

The socket member is apertured at one side to receive the extremity of the latch member 13a carried in the bracket 13c secured to the under face of the counter or base member 3. The spring 13b is provided for projecting the bolt 13a inwardly through the aperture provided in the socket member 13. The lower extremity of the socket member 13 is threaded to receive a tubular extension 13d having a cap or closure for the end thereof, as indicated at 13e. Slidably mounted within the socket member 13 and its extension 13d is a socket closure 14 having a stop flange or rim 14a formed on the lower end thereof. The spring 14b is disposed within the socket closure member, having its ends confined by the closure member and the cap, the purpose of this spring being to elevate the closure member to the position shown in Figure 17A upon retraction of the slidable mullion member to close the recess in the base member.

The forked rack or release member 12g has a threaded shank 12i on which is positioned the push handle or release member 12j, this member being arranged for sliding movement in a guide passage formed in the foot member 12b.

From the foregoing it will be observed that when one of the mullion members is moved downwardly to the position shown in Figures 13 and 14 of the drawings, the locking bolt or semi-rotatable shaft 12d will enter the socket member 13, forcing the closure therefor downwardly. As the mullion member reaches its extreme extended position, the latch-engaging shoulder 12m will be engaged by the latch member 13a, and in this way positively lock the mullion member against accidental displacement. When it is desired to raise the mullion member, the push handle 12j is forced inwardly causing the teeth 12h on the forked rack member to rotate the shaft or bolt 12d. Rotation of this bolt moves the latch release cam thereon into engagement with the nose of the latch member 13a, forcing the same out of the central bore in the socket member 13, whereupon the mullion member 5 is released and may be readily and easily raised or moved away from the counter or base member 3.

The sliding sash members 6 upon elevation thereof move through an opening in the upper portion of the framework or super-structure, and, in order to close this opening when the sliding sash members are lowered, I provide an aperture closing strip or channel, as indicated at 15, having the free edges thereof bent horizontally, as at 15a, to rest on the upper faces of the framework above the closure opening A. The ends of the channel strip 15 are provided with flanged plates 15b, as seen in Figures 20 and 21, these plates being formed with guide channels 15c adapted to ride on the outside guide strips 4e secured to the stationary mullion members 4.

The sliding sash members 6 are provided adjacent their lower edges with weather strip holding channels 16 for receiving weather strip or pack-

ing members 16b, as clearly seen in Figure 4 of the drawings. This packing member may be partially encased in a supplemental resilient holding strip 16a, if desired. Adjacent the lower edge of the sash, I arrange an inside closure member 16c in the form of a rectangular-shaped tube having vertical slots intermediate its length through which the securing screws are passed.

The upper edge of the sliding sash is provided with a resilient plate 6a secured thereto and extending downwardly in the plane of the sealing gasket 4c in the channel-shaped meeting rail 4a extending between the fixed mullion members. When the sash is moved to closed position, as seen in Figure 4, this flange 6a engages the strip 15c to provide a weather seal at this point.

Briefly describing the operation of my invention, we will assume that the parts are in the position shown in Figure 4 of the drawings, or, in other words, the window opening is closed. The operator or shop-keeper elevates the sliding sash after unlocking the same, and as the sash is elevated, the upper edge thereof will engage the closure plate 15, sliding the same upwardly along the guide rail 4e. As the sash is moved upwardly, the outwardly-extending guide flanges engage the guide members 4d, guiding the same. In order to elevate the mullion members, the operator depresses the push handle which releases the locking shaft from engagement with the locking bolt 13a, whereupon the mullion members may be moved upwardly or telescoped within the fixed mullion members, as shown in dotted lines in Figure 4. Under these conditions, it will be observed that the opening above the counter or base member 3 is unobstructed, as seen in Figure 1 of the drawings. The pivoted sash member 6b may also be released and swung outwardly to the dotted line position shown in Figure 4.

Figures 22 to 26 inclusive of the drawings show a slightly modified form having a rigid mullion member 5k extending across the opening, and secured in the upper super-structure or frame in any desired manner, as by bolts and screws 5l. This mullion member is preferably of U-channel formation, and is provided with a removable front closure plate 5m held in place by snaps or other suitable means. The rear face of the mullion member 5k has a wing channel parting strip 17 secured thereto for engaging the free edges of the sliding sash members 6f, there being a spring-pressed, U-shaped sash-retaining channel strip 18 resiliently held in engagement by the spring tensioned bolt 20, which is threaded into the spacing collar 18b secured to the inner face of the channel 18. A smaller U-shaped channel member 18a is secured to the rear face of the sash-retaining channel 18, as clearly seen in Figure 25 of the drawings, for receiving the lower or sliding sash screen closure members 19.

Interposed between the fixed mullion members 5k is a swinging or transom sash member 21 similar in construction and arrangement to the sash member 6b in my preferred form of the invention. The sliding sash member is indicated at 22, and has a lower sealing gasket 23 adapted to engage the base member 24 of the window opening. The sash member 22 is provided adjacent its upper extremity with an outwardly-extending flange 25 upturned to lie adjacent the rear face of the transom sash 21. The screen closure 26 is provided above the sliding sash 22 and arranged to move upwardly therewith. Rack members 27 are formed on the opposite edges of the sash members 22, as seen in Figures 25 and 75

26 of the drawings, these rack members being disposed in meshing engagement with pinions 28 fixed on the cross shafts 29. These cross shafts are journaled in the mullion members 5k, as seen in Figure 23, and each has an extension projecting into the interior of the mullion member and carrying a pinion 30 fixedly secured to the shaft. The pinion 30 meshes with a larger pinion 31, as seen in Figure 24, fixed to a drum member 32 on which is wound a flexible member or tape 33, a counterbalancing weight 34 being secured to the end of the tape. The purpose of this construction is to provide a counterbalancing means for the sliding sash member 22. As the sash member is moved up or down, the pinion 28 is rotated, and through the shaft and pinion 30, the larger pinion 31 is actuated, thus winding or unwinding the tape 33 against the action of the weight 34. In this form of the invention in which a screen member 26 is provided above the sliding sash 22, I provide an automatic release means for the pivoted or transom sash, this release means comprising a transom latch lever 11 pivotally secured to a bracket 11' carried on the transom sash frame. The lever 11 carries a locking flange 11'' arranged to be moved into locking engagement with the rear face of the sliding sash extension flange 25. A release pin 11a is also carried on the lever 11 and projects outwardly in the path 30 of the upwardly extending portion of the sash flange 25, so that upon upward movement of the sash the flange extension 25 will engage this locking pin 11a, rotating the lever 11 from the full line to the dotted line position as seen in Figure 27 of the drawings, thus moving the locking flange of the lever 11 out of engagement with the flange on the sliding sash. The means for swinging the sash outwardly, when released as just described, is identical with the transom sash swinging means described in my preferred embodiment of my invention and shown in Figure 9 of the drawings, and will not, therefore, be described.

In order to lock the sliding sash 22 against unauthorized movement, I provide a pivoted locking member 35 having teeth 36 adapted to engage the teeth on the pinion 28, when this locking member is moved to locking or full line position as shown in Figure 26 of the drawings.

50 Certain of the parts disclosed in connection with the modified embodiment in Figures 22 to 27 of the drawings are similar to those disclosed in my preferred embodiment, and these parts will be given the same reference numerals in both constructions.

Figure 28 discloses a slightly modified weather-sealing means for the lower edge of the sliding sash in which a plurality of sealing gaskets 16aa are provided.

60 I claim:—

1. In a device of the class described, a structure having an unobstructed opening, a closure member longitudinally movable across said opening to close the same, and longitudinally movable guide means for said closure member vertically movable into a position across said opening for guiding the closure member to and from closed position and for supporting the closure in closed positions.

70 2. In a device of the class described, a structure having an opening, a closure member movable across said opening to close the same, and telescopic guide means for said closure member movable across said opening for guiding the

closure member to and from closed position and for supporting the closure in closed positions.

3. In a device of the class described, a structure having an opening, a sliding sash closure member movable across said opening to close the same, and telescopic guide means for said closure member movable across said opening for guiding the closure member to and from closed position and for supporting the closure in closed positions.

10 4. In a device of the class described, a structure having an opening, a sliding sash closure member movable across said opening to close the same, telescopic guide means for said closure member movable across said opening for guiding the closure member to and from closed position and for supporting the closure in closed positions, and means for holding said guide means in guiding position.

20 5. In a device of the class described, a structure having an opening, a plurality of sliding mullion members movable across said opening, guide means for said mullions mounted on said structure, and a plurality of sliding sash members guided by said sliding mullion members and movable across said opening to close the same.

25 6. In a device of the class described, a structure having an opening, a plurality of sliding mullion members movable across said opening, guide means for said mullions mounted on said structure, a plurality of sliding sash members guided by said sliding mullion members and movable across said opening to close the same, and counterbalancing means for said sliding mullions to balance the weight thereof.

30 7. In a device of the class described, a structure having an opening, a plurality of sliding mullion members movable across said opening, guide means for said mullions mounted on said structure, a plurality of sliding sash members guided by said sliding mullion members and movable across said opening to close the same, counterbalancing means for said sliding mullions to balance the weight thereof, and separate sash balancing means for said sliding sash members.

35 8. In a device of the class described, a structure having an opening, a plurality of sliding mullion members movable across said opening, guide means for said mullions mounted on said structure, a plurality of sliding sash members guided by said sliding mullion members and movable across said opening to close the same, counterbalancing means for said sliding mullions to balance the weight thereof, separate sash balancing means for said sliding sash members, and locking means for retaining said sliding mullion members in position across said structure opening.

40 9. In a device of the class described, a building structure having an opening, a closure for said opening including a mullion-receiving support, a mullion member telescopically carried by said support and extendible across said structure opening, and a sliding sash member guided by said mullion member and independently movable across the opening to close the same.

45 10. In a device of the class described, a building structure having an opening, a closure for said opening including a mullion-receiving support, a mullion member telescopically carried by said support and extendible across said structure opening, a sliding sash member guided by said mullion member and independently movable across the opening to close the same, and latch-

ing means for holding said extensible mullion member in extended position across the opening.

11. In a building structure of the class described having an opening, a counter below said opening, a mullion support disposed above said counter, and spaced therefrom, a mullion member extensibly mounted in said support and vertically movable across the opening above the counter and having sash guide means, and a movable sash guided by said guide means and movable to close the last-mentioned opening.

12. In a building structure of the class described, having an opening, a base member horizontally extending across the bottom of said opening, vertically disposed mullion guide means mounted on said structure above the opening, a mullion member telescopically mounted in said guide means and extensible downwardly across said opening into engagement with said base member, sash guide means on said mullion member, and a sliding sash member operable in said mullion guide means and movable vertically across said opening into engagement with said base member to close the opening, said mullion and said sash being vertically movable away from said base member and when so moved to present an unobstructed opening.

13. In a building structure of the class described, having an opening, a base member horizontally extending across the bottom of said opening, vertically disposed mullion guide means mounted on said structure above the opening, a mullion member telescopically mounted in said guide means and extensible downwardly across said opening into engagement with said base member, sash guide means on said mullion member, a sliding sash member operable in said mullion guide means and movable vertically across said opening into engagement with said base member to close the opening, said mullion and said sash being vertically movable away from said base member and when so moved to present an unobstructed opening, and cooperative weather sealing means carried by said mullion and sash members.

14. In a building structure of the class described, having an opening, a base member horizontally extending across the bottom of said opening, vertically disposed mullion guide means mounted on said structure above the opening, a mullion member telescopically mounted in said guide means and extensible downwardly across said opening into engagement with said base member to close the opening, said mullion and said sash being vertically movable away from said base member and when so moved to present an unobstructed opening, cooperative weather sealing means carried by said mullion and sash members, and separate weather sealing means carried by said sash for cooperative engagement with said base member when said sash is moved to close the opening.

15. In a building structure of the class described, having an opening, a base member horizontally extending across the bottom of said opening, vertically disposed mullion guide means mounted on said structure above the opening, a mullion member telescopically mounted in said guide means and extensible downwardly across said opening into engagement with said base member, sash guide means on said mullion mem-

ber, a sliding sash member operable in said mullion guide means and movable vertically across said opening into engagement with said base member to close the opening, said mullion and said sash being vertically movable away from said base member and when so moved to present an unobstructed opening, cooperative weather sealing means carried by said mullion and sash members, separate weather sealing means carried by said sash for cooperative engagement with said base member when said sash is moved to close the opening, and a weather seal carried on the lower end of said mullion for engagement with said base member when said mullion is extended across said opening.

16. In a building structure of the class described having a wall opening, a plurality of fixed mullion members extending partly across said opening, a sash member disposed between said fixed mullions, sliding mullions telescopically disposed in said fixed mullion and extensible across the opening, and movable sash members carried by said sliding mullions and shiftable to close the opening when said sliding mullions are in extended position.

17. In a building structure of the class described having an opening, a plurality of mullions disposed across said opening, a horizontally pivoted sash disposed between said mullions in the upper portion of said opening, a vertically movable sliding sash carried by said mullions and movable to close the balance of said opening, locking means for said pivoted sash carried thereby for locking engagement with said sliding sash to retain the pivoted sash in closed position, and means operable by the sliding sash for automatically releasing said locking means upon upward movement thereof from its closed position.

18. In a building structure of the class described having an opening, a plurality of mullions disposed across said opening, a horizontally pivoted sash disposed between said mullions in the upper portion of said opening, a vertically movable sliding sash carried by said mullions and movable to close the balance of said opening, locking means for said pivoted sash carried thereby for locking engagement with said sliding sash to retain the pivoted sash in closed position, means operable by the sliding sash for automatically releasing said locking means upon upward movement thereof from its closed position, and means for automatically swinging said pivoted sash to open position when so released.

19. In a device of the class described, a structure having an unobstructed opening, a closure member movable across said opening to close the same, longitudinally movable guide means for said closure member vertically movable from a position exterior of the opening into a position across said opening for guiding the closure member to and from closed position and for supporting the closure in closed positions, and releasable locking means for retaining said guides in guiding position across the opening.

20. In a device of the class described, a building structure having an opening, a closure member movable across the opening to close the same, longitudinally movable guide means extensible across the opening for guiding said closure across said opening to and from closed position and for supporting the closure in closed position, said guide means being retractible from the opening subsequent to the movement of the closure member from the opening to provide a free and unobstructed opening in the building structure,

and releasable locking means at the side of the opening for positively retaining said guide means in guiding position across the opening and releasable to permit retraction of the guide means from its position across the opening.

21. In a building structure of the class described having an opening, a mullion guide member movably carried by the building structure at one side of the opening and movable to a position across the said opening and movable out of the opening to provide an unobstructed opening, a sliding sash member arranged to be guided by said mullion guide means to and from a position across said opening, and releasable locking means disposed at the other side of the opening

for releasably retaining the mullion member in its position across the opening.

22. In a building structure of the class described having an opening, a fixed mullion member extending downwardly partly across said opening, a removable mullion member carried by said fixed mullion member and movable to a position extending across the balance of the opening, and a sliding sash member in guiding cooperation with both of said mullion members and movable to completely close the opening when in one position and to move completely out of the opening when shifted to another position.
